MULTIPLE SWITCH ACTUATOR

Alwin B. Newton, Minneapolis, Minn., assignor to
 Minneapolis-Honeywell Regulator Company,
 Minneapolis, Minn., a corporation of Delaware

Application January 7, 1942, Serial No. 425,888

19 Claims. (Cl. 200—81.5)

The present invention is concerned with automatic controls wherein a plurality of switches, for instance, switches controlling poly-phase electrical circuits are to be actuated simultaneously.

The primary object of my invention is to provide means for simultaneously moving a plurality of switches or like devices from one position to another.

Another object of my invention is to provide an arrangement for simultaneously moving a plurality of switches from a first position to a second position wherein separate adjustments are provided for the points at which the switches are actuated from each position to the other; that is, if the switches are actuated automatically in response to a variable condition, the arrangement provides for independently adjusting the value of the condition at which the switches are moved from each position to the other.

Another object of the invention is to provide a control mechanism comprising an actuating member for actuating a plurality of devices, the actuating member being movable by snap acting mechanism.

Another object of the invention is to provide an actuating mechanism for automatic controls comprising a whiffletree type of lever, both ends of which are movable with a snap action.

Another object of the invention is to provide an actuating mechanism for a plurality of switches or the like comprising an actuator member for the switches, the member being movable with a snap action by means of a whiffletree type of lever having at least one end movable with a snap action.

My invention finds one application in controlling poly-phase circuits in systems wherein a poly-phase motor is used as a prime mover, for instance, the motor for driving the compressor of a mechanical refrigeration system as shown in the drawing. It is, of course, desirable that all the wires of the poly-phase circuit have their controlling switches opened and closed simultaneously. As pointed out above, it is the object of my invention to provide means for simultaneously opening and closing the various circuits.

In the drawings:

Figure 1 is a diagrammatic view partly in detail of one form of my multiple switch actuator.

Figure 2 is a modified form of my multiple switch actuator with a side of the casing removed so as to better illustrate the device.

In the drawing, numeral 10 designates generally a mechanical refrigeration system comprising a three-phase electrical motor 11 which drives a

refrigerant compressor 12 through a belt 13. The compressor is connected to a condenser 14 by a pipe 15 and the compressor is connected to an evaporator 16 by a pipe 17. The suction side of the compressor is connected to the evaporator by a pipe 18. Interposed in the pipe 17 leading to the evaporator is an expansion valve 20 which is of the superheat type adapted to maintain a constant degree of superheat at the outlet of the evaporator. The expansion valve 20 is of a well-known type, the operating mechanism including an expandible and contractible chamber which is connected to a thermal bulb 21 by means of a capillary tube 22, the thermal bulb being disposed in intimate heat exchange relationship with the pipe through which refrigerant is discharged from the evaporator so that the volatile liquid in the thermal bulb vaporizes and develops a pressure depending upon the temperature of the refrigerant leaving the evaporator.

The motor 11 is a three-phase motor and the three-phase circuit is comprised of wires 25, 26 and 27 which lead to respective switches 28, 29 and 30 located within a control device 31. One of the terminals of each of the switches is also connected to the wires 32, 33 and 34, respectively.

The construction and arrangement of the controller 31 constitutes the principal part of my invention. Each of the switches 28, 29 and 30 comprises a housing which may be made of Bakelite or the like and the switches are preferably of a snap acting normally open type. A preferred form of switch is shown in Patent Number 2,318,734, issued May 11, 1943. The switches are operated by plungers 35, 36 and 37, respectively, which close their respective switches when the plungers are pushed inwardly, the plungers moving outwardly causing the switches to open whenever the plungers are released. Obviously a given amount of inward movement must be imparted to each of the plungers to cause closure of their respective switches, and upon release of the plungers they will move outwardly a corresponding amount to open the switches.

All of the plungers engage in abutting relation with adjusting screws carried by a lever member 41 having an ear 42 pivoted to a bracket 43. By rotating the lever member 41 in a counter-clockwise direction the plungers are moved inwardly, and upon rotating the lever member 41 in a clockwise direction the plungers are permitted to move outwardly. By adjusting the screws the snapping points of the switches with respect to lever 41 can be nicely adjusted so that whenever

the lever is in a position to snap any one switch it is in a position to snap them all.

At the left end of the lever 41 there is secured a flexible bracket 44, part of which is spaced from the end of member 41, there being a screw 45 extending through the bracket 44 and member 41 for purposes which will presently be described.

Numeral 46 designates a lever of the whiffle-tree type having a downwardly extending projection 47 at its mid point which engages in 10 abutting relationship the bracket 44. The left end of the member 46 has an aperture 48 through which extends a stop pin 49 and the right end of the member 46 has an aperture 50 through which extends a stop pin 51. Numeral 52 designates a coil tension spring, the lower end of which is attached to an extending portion 53 at the left end of member 46, the upper end of the spring being attached to a member 54 which is engaged in screw-threaded relationship by an 15 adjusting screw 55 which extends through a sidewall of the casing 31, the purpose of the screw 55 being to adjust the tension of spring 52. Numerals 56 and 57 designate toggle members, one 20 end of each of which is engaged in a recess in the portion 53 of member 46. The other end of toggle member 57 engages a similar recess in a fixed abutment and the other end of toggle member 56 25 engages a recess formed in a resilient bracket member 58 suitably mounted within the casing of the controller 31. From the construction so far described, it is obvious that the toggle members 56 and 57 and the spring 52 are operable 30 to impart snap action to the left end of the whiffle-tree member 46. The spring rate of the toggle mechanism with respect to the spring rate of spring 52 is such that once the end of lever 46 starts to move, the movement will be with a snap. The upward force exerted by the toggle mechanism decreases faster than the force of spring 52 increases when member 46 moves downwardly. Thus the movement is with a snap.

The right end of the member 46 is movable with a snap action in exactly the same manner as the left end, the elements associated with the right end being identical with those on the left. The elements associated with the right end of the member 46 therefore bear the same reference characters as the corresponding elements on the left end of the member 46 but with the identifying letter *a*. Further description of the mechanism at the right end of the lever member 46 is therefore unnecessary.

The mechanism for actuating the whiffle-tree member 46 comprises an expandable and contractible member which is preferably a bellows located within a housing 64. The movable end of the bellows is attached to a stem 65 which engages the mid point of the member 46 so as to move the member in a downward direction when the bellows expands and to permit it to move upwardly under the influence of the tension springs when the bellows contracts. The interior of the bellows is connected to the pipe 18 by a tube 66 so that the bellows expands and contracts in accordance with the suction pressure of the refrigeration system.

At the right end of the lever member 41 is a bracket 44a corresponding to the bracket 44 except that it is not flexible having a screw 45a extending through it, this screw corresponding to the screw 45. Associated with the right end of the lever member 41 is a whiffle-tree which is the same as and corresponds to the whiffle-tree 46, its ends having snap acting mechanism asso-

ciated therewith, the same as the snap acting mechanism already described. Inasmuch as the details of the mechanism associated with the right end of lever member 41 are the same as those of the mechanism at the left end, the details at the right end bear the same reference characters with the identifying letters *a*, *b* and *c*. The bellows which actuates the lever 46a is connected to the pipe 15 by a capillary tube 67 so that the bellows expands and contracts in accordance with the discharge pressure of the compressor 12.

With the parts in the position shown, the projection 47a is spaced from bracket 44a, and as will presently be described, it does not engage the bracket 44a for actuating the lever 41 except in the event of an unduly high discharge or head pressure.

With reference to the operation, the springs 52 and 52b are normally adjusted so as to be under a greater tension than the springs 52a and 52c respectively. With the parts in the position shown, the switches 28, 29 and 30 are open and the refrigerating system is not in operation so that the suction pressure is rising. As the suction pressure rises, the bellows within housing 64 expands, and inasmuch as the spring 52a is adjusted so as to have less tension than the spring 52, the right end of member 46 moves downwardly as the bellows expands. The right end of member 46 is moved downwardly with a snap action as described above until the pin 51 engages the upper side of aperture 50. This occurs at a predetermined suction pressure determined by the adjustment of screw 55a. This movement of the right end of member 46 is of course imparted to the lever 41, the lever 41 being moved correspondingly in a counter-clockwise direction, the plungers 35, 36 and 37 being moved inwardly a predetermined amount but not enough to close the switches 28, 29 and 30. As the suction pressure continues to rise, expansion of the bellows within housing 64 will now cause the left end of member 46 to be moved downwardly, and the left end of member 46 will be snapped downwardly until the pin 49 engages the upper side of aperture 48, this occurring at a predetermined suction pressure which is dependent on the setting of screw 55. This snap movement of member 46 will likewise be imparted to the lever member 41 which will be again snapped in a counter-clockwise direction and the plungers 35, 36 and 37 will of course be snapped inwardly simultaneously and this time an amount great enough to simultaneously close the switches 28, 29 and 30. Closure of the switches will put the motor 11 in operation and the refrigeration system will operate to produce refrigeration.

By adjusting the screw 45 the relationship between the whiffle-tree member 46 and the lever 41 may be adjusted.

As the refrigeration system operates, the suction pressure will fall, and as it falls the bellows within housing 64 will contract. The left end of member 46 will now move upwardly first inasmuch as spring 52 is under greater tension than spring 52a, and the left end of member 46 will be snapped upwardly to the position to which it is shown in the drawings. This movement will of course be imparted to the lever 41 which will be correspondingly snapped in a clockwise direction so as to release the plungers 35, 36 and 37 so as to let them move outwardly a given amount but not enough to open their respective switches. As the suction pressure continues to fall and the

bellows within housing 64 continues to contract, the right end of member 46 will now move upwardly under the influence of spring 52a, and the right end of member 46 will be snapped upwardly until the stop pin 51 engages the lower side of aperture 50, as shown on the drawing. This snap movement will of course be transmitted to the lever member 41 which will be snapped a corresponding amount in a clockwise direction, relieving the pressure on the plungers 35, 36 and 37 and allowing them to simultaneously move outwardly to positions wherein their respective switches are opened.

From the foregoing, it can be seen that the switches 28, 29 and 30 are simultaneously actuated to their closed and open positions under the influence of the lever member 41. The suction pressure at which the switches are closed is determined independently by the adjustment of screw 55 which adjusts the tension of spring 52, this being true because spring 52 controls the snapping of the left end of member 46. The suction pressure at which the switches are opened is independently controlled by the adjustment of screw 55a which adjusts the tension of spring 52a, this being true because the tension of spring 52a determines the suction pressure at which the right end of member 46 will be snapped upwardly so as to cause the member 41 to be snapped to a position wherein the switches are opened.

The mechanism associated with the right end of the lever member 41 functions in exactly the same manner as the mechanism at the left end so that the description need not be repeated. The mechanism at the right end of the controller 31 will function to cause opening of the switches in the controller upon the occurrence of an unduly high head or discharge pressure. Stating this operation briefly, when the head pressure rises to a predetermined value, the right end of member 46a will be snapped downwardly first, the spring 52c having less tension than the spring 52b. At a higher predetermined head pressure, the left end of member 46a will be snapped downwardly and at this pressure the projection 41a will engage the bracket 44a moving the lever 41 in a clockwise direction to a position wherein the switches 28, 29 and 30 are open. The lever 41 will be held in a position wherein the switches are open until the head pressure decreases to a predetermined value at which both ends of the member 46a have snapped upwardly to the position shown in the drawing.

The bracket 44 provides a strain release device for relieving the strain when both the projections 47 and 47a are engaging their associated brackets; that is, these brackets relieve the strain at times when the suction pressure responsive device is attempting to close the switches when at the same time the head pressure responsive mechanism is holding the lever 41 in open position of the switches.

It will be noted that when the head pressure responsive mechanism has moved lever 41 to open position of the switches the head pressure must fall to a predetermined value at which the ends of lever 46a have snapped upwardly. This is a desirable characteristic.

Referring to Figure 2 of the drawings, I have shown a modified form of my invention, this form of the invention also employing a floating lever through which the switches are actuated, the floating lever being operated in a somewhat different manner in this form of the invention. In Figure 2 numeral 70 designates a generally rec-

tangular housing or casing within which the snap switches 71 and 72 are located. There may be two or more switches in the casing and the switches are of the same type as in the previous modifications. In the present modification the operating stems of the switches are designated by the numeral 73.

The actuating mechanism for the switches comprises a floating lever 76, which is actuated by an expandable and contractible bellows device within a housing 77, the bellows being connected to the suction side of the refrigeration system as in the previous embodiment by a tube 78. The bellows upon expansion actuates a stem 79 against the force of a spring within the housing, the tension of which may be adjusted by an adjusting screw 80 through which the stem 79 extends. The upper end of the stem 79 is attached to a ball 81 which is loosely disposed in an opening in the lever 76. Numeral 82 designates a flexible leaf, the right end of which is attached to the upper side of the lever 76, the leaf normally engaging the ball 81. Numeral 83 designates a similar leaf attached to the lower side of lever 76 and engaging the ball 81, the stem 79 extending through an opening in the leaf 83. The leaves 82 and 83 and the ball 81 form a strain release connection between the stem 79 and the lever 76, the resiliency of the leaves permitting relative movement between the stem 79 and the lever 76. The right end of lever 76 is movable between fixed stops 84 and 85 and the left end of lever 76 is movable between stops formed by two manually adjustable cams 86 and 87, both of these cams having a gradual rise, that is, a spiral contour and the cam 86 is mounted on a shaft which extends through a side wall of the casing 70 and which is adjustable, that is, rotatable by a manual adjusting knob 88. The cam 87 is similarly adjustable by a knob 89. Adjacent each of the manual adjusting knobs and rotatable therewith is an indicating dial to indicate the position of the respective cams.

At the right end of lever 76 is a downwardly extending bifurcated portion 90 and engaged between the bifurcations is the left end of a pivoted lever 95 pivoted on a pivot 96. The operating stems 73 of the switches abut adjusting screws 74 carried by a broadened portion of the lever 95, these screws serving the same purpose as the corresponding screws of the previous embodiment. The right end of lever 95 engages in a notch in the end of a toggle member 97, the opposite end of which is pointed and which engages in a seat near the end of a resilient spring bracket 98 the lower end of which is attached to a side wall of the casing 70. From the foregoing it can be seen that when the lever 95 is rotated in a clockwise direction the knee formed by the lever 95 and toggle member 97 will tend to straighten out and as it tends to straighten out the parts will move with a snap action toward a position wherein the members 95 and 97 lie along a straight line.

The operation of the device as so far described is as follows: Upon a rise in suction pressure occurring when the refrigeration system is not in operation the bellows within housing 77 is expanded against the force of the spring within the housing thus moving the left end of lever 76 upwardly until it engages the cam 86, this of course occurring at a suction pressure which will depend on the adjustment of cam 86. The right end of lever 76 so far remains in engagement with stop 85, then upon further increase in suction

pressure the right end of lever 76 will begin to move upwardly and as the lever 95 starts to rotate in a clockwise direction in the manner described above, the toggle mechanism will snap to a position wherein the right end of lever 76 is in engagement with stop 84. When the lever 95 is thus snapped the stems of all the switches are snapped upwardly, that is, inwardly to closed position of the respective switches and this of course occurs simultaneously with respect to all of the switches.

It is to be noted that a characteristic of this arrangement is that little or no operating pressure is applied to the member 73 until the switches are actually actuated. The force produced by the suction pressure is applied mainly against the spring within housing 77 and against the cam 86.

When the suction pressure falls due to operation of the system, the bellows within housing 77 will contract moving the left end of lever 76 downwardly until it engages cam 87 and this will occur at a suction pressure determined by the setting of cam 87. Upon further decrease in suction pressure the right end of lever 76 will be moved downwardly thus moving lever 95 in a counter clockwise direction and causing it, by reason of the toggle mechanism to snap into the position shown in Figure 2. When lever 95 is thus snapped the stems of all the switches will of course be moved downwardly simultaneously with a snap action to open position of the switches.

From the foregoing it is apparent that with the arrangement of Figure 2 the cut-in and cut-out pressures of the switches are determined independently by adjusting the knobs 88 and 89.

Numerical 100 designates a second housing similar to housing 77 associated with the outside of casing 70. Housing 100 contains an expandable and contractible bellows, the interior of which is connected to the high pressure side of the refrigeration system by a tube 101 so that the bellows expands and contracts in accordance with head pressure of the system. The bellows expands in response to head pressure against a spring, the tension of which is adjustable by adjusting nut 102, the bellows actuating a stem 103 which extends through the nut 102. Numerical 104 designates a lever pivoted on a pivot 105, the left end of the lever being connected to portion 90 of lever 76 by link 106 and the right end of the lever being engageable by the stem 103. If the head pressure rises to a predetermined value when member 73 is in closed position of the switches the stem 103 will engage lever 104 rotating it in a counterclockwise direction so as to snap the lever 95 to open position of the switches. This will occur even though the suction pressure responsive device has positioned the lever 76 in a position wherein normally the switches are closed, the strain release connections between stem 79 and lever 76 permitting downward movement of the right end of lever 76 under these circumstances. If the switches are opened by the head pressure responsive device the head pressure will have to drop somewhat before the switches can be reclosed by the suction pressure responsive device.

The suction pressure device of my invention may operate between fairly widely different pressures, that is, over quite a wide range of pressure so that fairly widely differing forces are developed by these pressures. However, by reason of my particular arrangement, these forces which sometimes may be quite large are not im-

parted to the actuating member 73 of the switches. In practice, the switches may be constructed of relatively small and inexpensive parts and so that only very small forces are required to move the switches from one position to the other. In the embodiment of Fig. 2 the switches may of course be actuated by plungers in the same manner as in Fig. 1.

The embodiments of my invention which I have disclosed herein are representative of its preferred forms. Various other forms and modifications of the invention will occur to those skilled in the art and therefore the disclosure is to be interpreted in an illustrative rather than a limiting sense. The invention is to be limited only in accordance with the claims appended hereto.

I claim as my invention:

1. In apparatus of the character described, in combination, control means including a floating lever, means for limiting the movement of the lever, means for causing said lever to move between first and second positions with a snap action, and means comprising a plurality of control devices actuatable by said lever and adjustment means for regulating the actuation of each of said control devices by said lever.

2. In apparatus of the character described, in combination, control means including a floating lever, means for limiting movement of the lever, means to be controlled operable in response to movement of an intermediate point of the lever, and means for causing each end of the lever to move between first and second positions with a snap action.

3. In apparatus of the character described, in combination, control means comprising a lever, means operable upon an intermediate point of the lever for moving it, means to be controlled operable in response to movement of an intermediate point of the lever, a plurality of snap acting means associated with an end of the lever to cause said end to move between first and second positions with a plurality of snap actions whereby such snap action is imparted to said means to be controlled.

4. In apparatus of the character described, in combination, control means comprising a floating lever, means operable upon an intermediate point of the lever for moving it, means to be controlled operable in response to movement of an intermediate point of the lever, means associated with the ends of the lever to cause each end to move between first and second positions with a snap action, whereby the snap action is imparted to said means to be controlled.

5. In apparatus of the character described, a control mechanism comprising a floating lever, means whereby each end of the lever is movable between two positions with a snap action, control means arranged to be moved from one position to another by the lever, said control means being in one of its said positions when both ends of the floating lever have been snapped one way, and said control means being in its other position when both ends of the floating lever have been snapped the other way.

6. In apparatus of the character described, in combination, a plurality of devices adapted to be snapped between first and second positions, means comprising a control member, means associated with said control member comprising automatic condition responsive snap acting mechanism for causing said control member to simultaneously actuate said devices, said last means being independently adjustable so as to

regulate the value or degree of the condition at which the devices are actuated to each position.

7. In apparatus of the character described, in combination, a plurality of devices adapted to be snapped between first and second positions, means comprising a control member, means associated with said control member including a floating lever having means arranged to cause each end of the lever to move between two positions with a snap action, means for independently adjusting the snapping of each end of the lever, said lever being so related to said control member that snapping of one end of the lever governs operation of the control devices to the first position and snapping of the other end of the lever governs operation of the control devices to the second position.

8. In apparatus of the character described, in combination, a control device, an actuator for the device, means for moving the device comprising a first condition responsive means arranged to move the device between open and closed positions, said moving means being so constructed and arranged as to provide for independently adjusting the values or degrees of the condition at which the device is opened and closed, another means for moving the actuator comprising a second condition responsive means arranged to move the device between open and closed positions, said other means being so constructed and arranged as to provide for independently adjusting the values or degrees of the condition at which the device is opened and closed.

9. In apparatus of the character described, in combination, a control device movable between first and second positions, an actuator for the device, means for moving the device comprising condition responsive mechanism having a floating lever arranged to impart motion to the actuator, means whereby the motion imparted to the actuator is snap movement, adjustable resilient means associated with a first point on said lever and adjustable resilient means associated with a second point on said lever, the parts being so arranged that the adjustment of one resilient means controls the value or degree of the condition at which the device is moved to one position and the adjustment of the other resilient means controls the value or degree of the condition at which the device is moved to the other position, another means for moving the device comprising a second condition responsive mechanism having a floating lever and mechanism arranged to impart snap motion to the actuator, adjustable resilient means associated with a first point on said last mentioned lever and adjustable resilient means associated with a second point on said last mentioned lever, the parts being so arranged that the adjustment of one resilient means controls the value or degree of the condition at which the device is moved to one position by said last lever and the adjustment of the other resilient means controls the value or degree of the condition at which the device is moved to the other position by said last lever.

10. In apparatus of the character described, in combination, a switch, switch actuating means comprising a floating lever, means whereby each end of the lever is moved with a snap action, the movement being imparted to the switch, means for independently adjusting the snapping of each end of the lever, said actuating means comprising a second floating lever, means whereby

each end of the second lever is moved with a snap action, the movement being imparted to the switch, and means for independently adjusting the snapping of each end of the second lever, the adjustments of the snapping of the floating levers controlling the opening and closing of the switch.

11. In apparatus of the character described, in combination, a control device movable between first and second positions, an actuator for the device, means for moving the device comprising condition responsive mechanism having a floating lever arranged to impart motion to the actuator, means whereby the motion imparted to the actuator is snap movement, adjustable resilient means associated with a first point on said lever and adjustable resilient means associated with a second point on said lever, the parts being so arranged that the adjustment of one resilient means controls the value or degree of the condition at which the device is moved to one position and the adjustment of the other resilient means controls the value or degree of the condition at which the device is moved to the other position.

12. In apparatus of the character described, in combination, control mechanism comprising a lever arranged to pivot about any one of a plurality of points as fulcrums, pressure responsive means for moving the lever, means forming stops between which one end of the lever is movable, and spring toggle snap mechanism associated with the other end of the lever whereby said other end of the lever is snapped from one position to another, the lever upon being actuated by the pressure responsive means engaging one or the other of said stops before tripping the spring toggle mechanism.

13. In apparatus of the character described, in combination, control mechanism comprising a lever arranged to pivot about any one of a plurality of points as fulcrums, pressure responsive means for moving the lever, means forming stops between which one end of the lever is movable, and spring toggle snap mechanism associated with the other end of the lever whereby said other end of the lever is snapped from one position to another, the lever upon being actuated by the pressure responsive means engaging one or the other of said stops before tripping the spring toggle mechanism and at least one of said stops being adjustable to adjust the pressure at which the spring toggle mechanism is tripped.

14. In apparatus of the character described, in combination, control mechanism comprising a lever arranged to pivot about any one of a plurality of points as fulcrums, pressure responsive means for moving the lever, resilient means resisting said pressure responsive means, means forming stops between which one end of the lever is movable, snap mechanism associated with the other end of the lever whereby said other end of the lever is snapped from one position to another and a plurality of switches actuatable simultaneously by said lever and snap mechanism.

15. In apparatus of the character described, in combination, control mechanism comprising a lever arranged to pivot about any one of a plurality of points as fulcrums, pressure responsive means for moving the lever, resilient means resisting said pressure responsive means, means forming stops between which one end of the lever is movable, snap mechanism associated with the other end of the lever whereby said other end of the lever is snapped from one position to an-

other, a plurality of switches actuatable simultaneously by said lever and snap mechanism; and a second pressure responsive means arranged to be operable to move the other end of the lever to open position of the switches.

16. The combination comprising, a plurality of control devices adapted to be actuated between first and second control positions, means comprising a control member, means associated with said control member comprising automatic condition responsive snap acting mechanism for causing said control member to actuate said control devices, and independent adjustment means so constructed and arranged as to regulate the actuation of each of said control devices by said control member.

17. In apparatus of the character described, in combination, control means including a floating lever, means for limiting the movement of the lever, means for causing said lever to move between first and second positions in a plurality of snap action steps and a control device actuated by said lever.

18. The combination comprising, a control de-

vice adapted to be moved between first and second positions, a control member, means associated with said control member comprising automatic condition responsive snap acting mechanism for causing said control member to actuate said control device in a plurality of snap action steps between said first and second positions.

19. In combination, comprising a control device adapted to be moved between closed and open positions under one set of conditions, a control member, means associated with said control member comprising automatic condition responsive snap acting mechanism for causing said control member to actuate said control device in a plurality of snap action steps between said closed and open positions, and a second means associated with said control member comprising automatic condition responsive snap acting mechanism for causing said control member to actuate said control device in a plurality of snap action steps between open and closed positions under a second set of conditions.

ALWIN B. NEWTON.
